ABSTRACT

In winding a great number of filament yarns or tows in position parallel to each other after treatments such as drawing and heat-setting, a rotatable disc having at least two rollers coming in contact with the yarn is disposed between the last roller available for said treatments to the yarn and a take-up apparatus. Said rollers are used interchangeably with each other by rotating said disc, and when the yarn has wrapped itself around one of the rollers owing to yarn breakage or loosening, the roller with the wrapped yarn is replaced by the other roller by rotating the disc to insure continuity of operations.

BROKEN YARN WINDING APPARATUS

The present invention relates to improvements in a winding apparatus for broken yarns. It is the object of the invention to accommodate a roller around which the yarn has wrapped itself during the operation because of yarn breakage or loosening and remove the obstacle of the operations in the early stage.

When a number of filament yarns or a number of tows in parallel rows are drawn or subjected to other treatment, the yarns discharged from the last process roller in the drawing apparatus are led to a subsequent take-up apparatus. If any yarn is broken between this take-up apparatus and the process roller, it wraps itself on the process roller (i.e. licking occurs). In order to remove the licking, the whole of the processing apparatus must be suspended. If the wrapped yarn is left adjacent running yarns giving rise to yarn breakage. Therefore any yarn which has wrapped itself around a roller should quickly be removed. If licking occurs frequently, the efficiency of operations remarkably diminishes.

And when filament yarns or tows are to be threaded from the last process roller in the drawing apparatus to the take-up apparatus, a suction gun is used for sucking each yarn or each tow and thereby taking up the yarn onto the rotating bobbin in the take-up apparatus. In this case, tension between the last process roller and the take-up apparatus suddenly lowers, and the filament yarn or tow frequently wraps itself on the last process roller, so that the efficiency of the apparatus also is diminished.

In order to eliminate said defects of the winding apparatus as quickly as possible, a rotatable disc on which two or more rollers (hereinafter called "relief rollers" to distinguish from the other rollers) are mounted is disposed between the last process roller and the take-up apparatus. It is desired to locate the relief rollers as near as possible to the last process roller. In the present invention, the yarns which have left the last process roller are led to the take-up apparatus through relief rollers. When any yarn is broken or loosens between the relief rollers and the take-up apparatus, it wraps itself around one of the relief rollers. At this time, the winding operations are continued by rotating the disc so as to replace the relief roller wrapped by the yarn with the other relief roller. The relief roller with the wrapped yarn is then set aside, and cleared of the yarn, and made ready for the future shifting for the other relief roller.

Hence continuity of the winding operations can be insured with the winding apparatus in the present invention simply by using interchangeably the relief rollers when yarn breakage or loosening occurs.

Further according to this invention a roller is preferably provided at a fixed position between the last process roller and the relief rollers in the same horizontal plane as the last process roller. This roller will be referred to as "a fixed roller" to distinguish from the other rollers.

Still further the winding apparatus in the present invention is so designed as to impart the lowest possible tension to the yarns by the special finish of the fixed roller surface and the difference in peripheral speed between the relief rollers and the fixed roller. Thus it is the main object of the present invention to make the yarn, which is broken or loosened, wrapped itself around one of the relief rollers instead of around the last process roller and thereby to prevent the discontinuation of the operation, and increase the rate of production.

FIG. 1 is a perspective view showing an embodiment of the present invention.

FIG. 2 and FIG. 3 are perspective views of the fixed roller.

FIG. 4 is a partial, vertical section of the relief roller in a roller system.

FIG. 5 is a front view of the relief roller as shown in FIG. 4.

FIG. 6 is a cross sectional view of one of the relief rollers.

One embodiment of the present invention will be described below referring to the drawings.

In FIG. 1 fixed roller 3 and relief rollers 5a and 5b mounted on rotatable disc 4 are disposed between last process roller 1 (such as a drawing roller in drawing apparatus) and take-up

apparatus 2a, 2b, 2c, and 2d. As shown in FIGS. 4 and 5, rotatable disc 4 is fitted with driving main shaft 7 with gear 8 attached. It is desired that main shaft 7 be fitted into disc 4 with bearing. Main shaft 7 is rotated by a power source (not shown) to give a predetermined number of revolutions.

A guide 13 is spaced around disc 4, while handle 12 is provided on the periphery of back plate 11 integral with and spaced behind said disc 4. Relief rollers 5a and 5b are supported by the shafts 5a' and 5b' which penetrate disc 4 and back plate 11 supported with bearings mounted thereon. Relief rollers 5a and 5b are rotated in the same direction by gears 9 and 10 attached to shafts 5a' and 5b' respectively, which mesh with gear 8 of main shaft 7. With such mechanism, it is possible to shift the position of roller 5a to that of roller 5b by rotating the disc 4 with handle 12. Instead of the handle, a gear may be provided on the periphery of the back plate 11. This gear is engaged with another gear (not shown), and the position of roller 5a is shifted to that of roller 5b by rotating said another gear. Suppose that roller 5a is used as a guide for the yarns and a broken yarn wraps on the roller 5a. The wrapped yarn would then cause entanglement with adjacent running yarns. However, disc 4 is rotated to replace roller 5a wrapped by broken yarn with roller 5b. Then it is possible for the other yarns to continue to run, and roller 5a can be taken care of separately.

Fixed roller 3 is placed before disc 4 and may be rotated freely or positively.

In FIG. 6, the back periphery of the relief roller is provided with an annular slot 59 in which one end of lever 60 is inserted with clearance. The other end of said lever 60 is fixed to the frame pivotably at 62 by means of a solenoid 61. Mounted on the shaft 5a' is a truncated cone, which when said roller 5a is allowed to move backwardly by a spring, comes into frictional engagement with a surface (a) of a hollow member secured to the inner surface of the relief roller 5a. When said roller 5a is moved forwardly by the lever 60, the cone is disengaged from the hollow member.

In FIG. 1 a number of filament yarns or tows 6a, 6b, 6c, and 6d treated with the processing apparatus, for instance a drawing device, pass under fixed roller 3 via last process roller 1, and are led to relief roller 5a and taken up onto the bobbins in take-up apparatus 2a, 2b, 2c and 2d.

Suppose that a filament yarn 6a is led from process roller 1 to take-up apparatus 2a, and the tension of the yarn lowers. In the conventional winding apparatus, this loose yarn would wrap itself around roller 1. In such case, the whole operation must be suspended to remove the wrapping of the yarn and to thread it into the take-up apparatus. On the other hand, in the present invention when loose yarn 6a wraps itself around relief roller 5a, relief roller 5a is shifted to the position of roller 5b, and roller 5b occupies the position of roller 5a by way of the rotation of disc 4. Yarn 6a leaving the group of running yarns through the position shifting of roller 5a does not affect the remaining yarns. Consequently, there is no need to suspend the running of the yarns, and the entangled yarn on roller 5a can be attended to outside the production line.

It is essential that relief rollers 5a and 5b are positively rotated. If they are allowed to rotate freely, the frictional resistance against the yarn increases, tension at the time of the string-up decreases, and licking deteriorates. In order to prevent licking on the process roller when the yarn has been loosened, it is preferred that the peripheral speed of roller 5a or 5b be slightly higher than that of the process roller and the yarn tension between the two thus be increased. Further to insure the wrapping of yarn around one of the relief rollers, a contact angle of yarn with the relief rollers is preferably 150° or above. The above is an embodiment using two interchangeable rollers, but the rollers are not limited thereto. Three or more may be employed.

As mentioned above, the surface of fixed roller 3 coming in contact with the yarn is coarsely finished by blasting an abrasive against the surface of the roller, and its peripheral speed is lower than that of the relief roller. In order to fully effect the

functioning of winding device in the present invention, any broken or loose end should always wrap itself around one of the relief rollers instead of the other rollers. In order that yarn may wrap itself around either one of the relief rollers, it is necessary that there be yarn tension between fixed roller 3 and the relief roller 5a or 5b kept at a certain value (depending upon the form of product). The above tension lies between fixed roller 3 and the relief roller (hereinafter called T_2), but a similar tension is seen between process roller 1 and fixed roller 3 (hereinafter called T_1). In like manner, yarn tension between the relief roller and the take-up apparatus is called T_3 . In the present invention T_3 is most important, but T_1 and T_3 should be taken into consideration together with T_2 . To give T_2 to the yarn, it is indispensable that there be yarn tension between the last process roller and the take-up apparatus, which can be generated by making greater the peripheral speed of the take-up mechanism than that of the last process roller. Between those rollers are disposed the fixed and relief rollers, and in view of the friction between the yarn and those rollers, T_1 , T_2 , and T_3 become possible. If said friction is not present, yarn tension will take a specified value and differences among T_1 , T_2 , and T_3 will disappear. The above is a description of yarn tension at the time when a broken end wraps around the relief roller. If this yarn tension is discussed in the light of yarn quality such as dyeability and fuzzing, it is undesirable to impart a high tension to the yarn after drawing, heat-setting, or other processes, and the lowest possible yarn tension (T_1 , T_2 , and T_3) between the last process roller and the take-up apparatus is desirable. However, T_2 must have a minimum value sufficient to insure that any broken or loose yarn wraps itself around the relief roller. For this reason T_2 has to have a specified value. But as T_2 is determined relative to T_1 , T_1 is preferably as low as possible. In other words, with a smaller T_1 , the necessary value of T_2 can be lowered.

To meet the above requirements, the surface of fixed roller 3₁ is coarsely finished (See FIG. 2.) or the diameter of fixed roller 3₂ is arranged to be smaller than that of the relief rollers (See FIG. 3.). The friction coefficient between yarn and a metallic roller is experimentally known as being the smallest with a roller having coarsely finished surface (Roughness is 5 to 11 S.). Thus if the friction coefficient is small, and T_1 is

small, the yarn easily wraps itself around the relief roller even under smaller T_2 tension. If the diameter of fixed roller 3 is smaller than that of the relief roller and thereby the peripheral speed of the latter roller is made slightly greater than that of the former roller, T_1 is smaller than T_2 . In the same way as with the coarsely finished roller, the yarn wraps itself easily around the relief roller.

As stated above, in the present invention all the broken ends or loose yarns in the winding apparatus holding a great number of yarns are adapted to be wound onto the relief roller. Without effecting other adjacent running yarns, the entangled yarn can be removed. Thus waste yarn at the time of string-up is slight and overall efficiency of the winding device is enhanced.

15 We claim:

1. A broken yarn winding apparatus positioned between a processing apparatus for treating a plurality of parallel yarns and a take-up apparatus for winding said plurality of yarns, said broken yarn winding apparatus comprising a fixed roller 20 mounted after said processing apparatus, a rotatable disc disposed between said fixed roller and said take-up apparatus, at least two relief rollers mounted on said disc and extending therefrom transversely of the direction of movement of said yarns, one of said relief rollers adapted to be engaged by said 25 yarns, means for positively rotating said relief rollers about the axes thereof with respect to said disc; and means for rotating said disc, whereby when one of said yarns becomes tangled around said one relief roller, said one relief roller is moved out of contact with the remainder of said yarns and another of said 30 relief rollers is brought into engagement with said remainder of said yarns.

2. A broken yarn winding apparatus as claimed in claim 1, wherein the surface of said fixed roller is coarsely finished.

3. A broken yarn apparatus as claimed in claim 1, wherein 35 said fixed roller is rotatable such that the peripheral speed thereof is less than the peripheral speed of said relief rollers.

4. A broken yarn apparatus as claimed in claim 1, further comprising a shaft mounting each of said relief rollers on said disc, and means for longitudinally moving said relief rollers 40 along said shafts for engagement and disengagement therewith.
